(57) **CLAIM**

The ornamental design for packaging for firecrackers, as shown and described.

DESCRIPTION

FIG. 1 is an upper perspective view of the packaging for firecrackers according to the present invention, the dashed lines being for environmental purposes to show spiral wound rolls of firecrackers within the packaging and forming no part of the claimed design;

FIG. 2 is an elevational view thereof;

FIG. 3 is a top plan view thereof; and,

FIG. 4 is a bottom view thereof.
